UNITED STATES PATENT OFFICE.

HERMAN F. STAHLER, OF BROOKLYN, ASSIGNOR OF ONE-HALF TO BREWSTER & COMPANY, OF NEW YORK, N. Y.

DESIGN FOR A LAMP.

SPECIFICATION forming part of Design No. 20,671, dated April 14, 1891.

Application filed January 7, 1891. Serial No. 377,040. Term of patent 7 years.

To all whom it may concern:

Be it known that I, HERMAN F. STAHLER, a citizen of the United States, residing at the city of Brooklyn, in the county of Kings and State of New York, have invented and produced a new and original Design for Lamps, of which the following is a specification, reference being had to the accompanying drawings, forming a part of the same.

10 The invention relates to a design to be imparted to lamps; and it consists of the novel shape and configuration herein shown and claimed.

In the accompanying drawings, Figure 1 represents a face view of a carriage-lamp embodying my design, and Fig. 2 is a plan view of the same.

My design consists of the body part A and the top or cover D.

20 The complete design resembles a pond-lily. The body part A consists, mainly, of the convexly-curved sides shaped and outlined to represent the petals of a pond-lily. The lower portion B of this body part A is shaped 25 and outlined to represent the calyx of a flower.

The downwardly-extending part C of the lamp represents the stem or a portion of the stem of the flower.

The upper portion or cover D consists of upwardly and outwardly extending projections surmounted by a central spherical form. This cover D as a whole resembles and represents the pistil of the flower constituting the complete design. A cover substantially like this cover D forms part of the design of another application filed by me on even date herewith and serially numbered 377,039, and is separately claimed in said application, and is therefore not herein separately claimed.

What I claim is—

1. The design for lamps, consisting of the body part A, substantially as shown.
2. The design for lamps, consisting of the body part A and the cover D, substantially as shown.

HERMAN F. STAHLER.
